UNITED STATES PATENT OFFICE

CARL F. ELLSWORTH, OF COLLINGSWOOD, NEW JERSEY, ASSIGNOR TO THE R. M. HOLLINGSHEAD CO., OF CAMDEN, NEW JERSEY, A CORPORATION OF NEW JERSEY

LIQUID SPRAYER AND METHOD OF MAKING THE SAME

Application filed April 23, 1931. Serial No. 532,197.

My invention relates to a liquid sprayer and method of making the same, and it relates more particularly to a certain method of making a suction siphon sprayer including an 5 apron, by which a great deal of the expense and difficulty of former methods is eliminated, and by which a minimum of solder is used.

An object of my invention is to simplify the 10 construction of suction siphon sprayers. Another object of my invention is to so design a suction siphon sprayer that the time and expense of making the same is reduced to a minimum while the strength and efficiency 15 of the completed sprayer is greatly increased.

With the above and other objects in view, my invention consists broadly of the novel construction and arrangement of certain parts, whereby they co-act to hold each other 20 in place so that by merely slipping each into its own place, it is held by the position of the others; and by sealing the assembled parts with two drops of solder so placed that the 25 whole is thereby locked into a strong and permanently assembled sprayer ready for use.

For the purpose of illustrating my invention, I have shown in the accompanying drawings one form thereof which is at present preferred by me, since the same has been found in practice to give satisfactory and reliable results, although it is to be understood 30 that the various instrumentalities of which my invention consists can be variously arranged and organized and that my invention is not limited to the precise arrangement and organization of the instrumentalities as herein shown and described.

Referring to the drawings in which like 40 reference characters indicate like parts:

Figure 1 represents a side elevational view, partly in section along the line 1—1 of Figure 2, of the hand pump to which my invention is applied.

Figure 2 represents a front elevational view 45 of the same.

Figure 3 represents a front elevational view of the apron embodying my invention.

Figure 4 represents a top plan view of the 50 apron embodying my invention.

Figure 5 represents an elevational view in section along line 5—5 of Figure 3.

Figure 6 represents a front elevational view of the siphon tube embodying my invention.

Figure 7 represents a top plan view of the 55 siphon tube.

Figure 8 represents a top plan view of a cap embodying my invention.

Figure 9 represents an elevational view, in 60 section, along line 9—9 of Figure 8.

Figure 10 represents a sectional view of the hand pump with the apron attached.

Figure 11 represents a sectional view of the hand pump with the apron and siphon tube 65 attached.

Figure 12 represents a sectional view of the hand pump with the apron, siphon tube, and cap attached, the latter being soldered into permanent position.

Figure 13 represents a view similar to that 70 shown in Figure 12, with the addition of a sealing washer in the cap, illustrating the complete assembly of the sprayer construction.

Figure 14 represents a front elevational 75 view of the completely assembled sprayer ready for use.

Figure 15 represents a top plan view of the completely assembled sprayer, partly in 80 section, along the line 15—15 of Figure 14.

Figure 16 represents a sectional view along line 16—16 of Figure 12.

Figure 17 represents a bottom plan view 85 of the hand pump and cap in proper position for soldering, illustrating the relative position of the cap and longitudinal pump seam.

According to my invention, I provide a hand operated air pump 17, having a sheet 90 metal spraying or discharge head 19 permanently attached to the cylindrical body 18 thereof, by means of the lock seam forming the bead 20, and extending inwardly into the pump, forming a recess 21 between the inner 95 cylindrical wall of the spraying head 22 and the inclined wall 23 and having a flat portion 24 in the same plane as the front circular edge of the bead 20 and having a central depression 25 therein, and a central discharge aper- 100

ture 26, through which the air is ejected by the hand-pump.

According to my invention, I also provide a generally semi-circular apron 27 having a circular skirt 28 extending generally transversely thereof and adapted to snap onto the bead 20 of the spraying head, and to interlock or to "hook" onto the same, and having also a lower straight edge portion 29 adapted to snap into the recess 21 of the spraying head and to be held by the inner cylindrical wall 22 thereof, and having further an inner depression 30 leading to an aperture 31 adapted to permit the passage of the siphon tube 32 therethrough. The apron of my invention also has an outwardly extending front portion 33 adapted to catch and to receive the waste dripping of the spraying fluid, said outwardly extending portion having a slightly raised portion 34 adapted to partially surround and to hold the siphon tube in place against the front flat portion 24 of the spraying head, as seen more particularly in Figure 11;—said apron having further a semi-circular cut-out portion 35 adapted to permit the free forward ejection of the sprayed fluid.

According to my invention, I further provide container retaining means such as the screw cap 36 for a bottle or other fluid container, such as the can 39; said cap having a hole 37 through which the siphon tube 32 passes; a depression 38 adapted to permit the top 40 of the cap 36 to lie against the cylindrical wall 18 of the hand pump 17 without interference from the bead 20, said bead passing into the depression 38; and having also a soldering aperture 41, the function of which will be described hereinafter.

The siphon tube 32 is of conventional construction having a wall 42 and an inner passageway 43.

In assembly, the apron 27 is snapped onto the spraying head 19 by means of the skirt 28 and the straight edge portion 29 of the apron acting against the bead 20 of the spraying head, and the inner cylindrical wall 22 thereof, respectively.

The siphon tube 32 is then passed through the aperture 31 of the apron 27; and forced upward between the raised portion 34 of the apron and the flat portion 24 of the spraying head, and pushed into operative relation with the discharge opening 26 of said spraying head.

In this process, the siphon tube forces outwardly the raised portion 34 of the apron 27, thereby creating a tension in the apron, which results in the apron tautly retaining the bead 20. In this manner, the siphon tube 32 permanently interlocks the apron 27 with the discharge head 19. The tension thus created, in turn forces the siphon tube 32 against the discharge head flat portion 24 and the outer bead edge 44, thereby holding the siphon tube in place.

The siphon tube 32 is then slipped into the aperture 37 of the cap 36 so that the top cap surface 40 lies flush against the cylindrical body portion 18 of the pump 17 with the solder hole 41 extending towards the pump wall behind the bead, as seen more particularly in Figure 12. The cap 36, siphon tube 32, and apron 27 are now adjusted so that while in assembled relationship, the cap may lie against the cylindrical pump body 18 and the seam 45 giving the cap a two-line support, as seen more particularly in Figures 16 and 17. Thus the top surface 40 of the cap 36 rests against the seam 45 and against the cylinder 18, eliminating any tendency of the cap to rotate around the cylinder. Solder 46 is then passed from the inside of the cap through and around the solder hole 41 permanently attaching the cap to the cylinder. Solder 47 is also applied to the portion of the siphon tube 32 immediately adjacent the inner portion of the top 40 of the cap 36, eliminating any possibility of the siphon tube 32 being pushed up or down. A suitable sealing washer 48, having a single hole 49 to permit the passage of the washer over the siphon tube 32 is slipped over the siphon tube 32 and into the cap 36 to seal the upper portion of the cap from corrosion and further to seal the contents of the container 39. In this manner, while the construction of the sprayer is exceptionally strong, no solder is normally visible, either above or inside the cap.

It will be noted that in the process herein described, no solder is applied until all the parts are assembled, and that this assembly is so simple that it may be done in almost an instant, it being merely necessary to snap the apron onto the spraying head, push the siphon tube through the apron into operative relationship with the pump discharge hole and to slip said siphon tube through the cap so that the cap rests in its proper position against the pump cylinder.

The advantages of this novel process are manifold, and reside chiefly in the strong sprayer produced, in the greatly reduced time necessary to assemble and construct a suction siphon sprayer, and in the greater efficiency of such construction, there being no great skill required to quickly assemble the sprayer, or to put two drops of solder into the cap.

I am aware that the invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what

I hereby claim as new and desire to secure by Letters Patent is:

1. The method of constructing liquid sprayers which consists of providing a hand pump having a discharge head with a discharge opening therein; said discharge head attached to the hand pump by a bead; an apron having a resilient bead-engaging flange, and having a flangeless bead-engaging portion, and having also a siphon-tube-receiving aperture; a siphon tube; and a container retaining means, said retaining means having a siphon-tube-receiving aperture; and assembling the sprayer by attaching the apron to the discharge head by snapping the resilient flange of the apron onto the bead and interlocking the bead with the flangeless bead-engaging portion; inserting the siphon tube through the aperture in the apron into interlocking juxtaposition to the apron and discharge head, and positioning the siphon tube in operative juxtaposition to the discharge opening in said discharge head; inserting the free end of the siphon tube into said aperture therefor in the container-retaining means, and positioning said retaining means in abutting relation to the pump wall; soldering the container-retaining means to the pump wall, and soldering the siphon tube 50 to a portion of the assembled sprayer.

2. The method of constructing liquid sprayers which consists of providing a hand pump having a discharge head with a discharge opening therein, said discharge head attached to the hand pump by a bead; an apron having a resilient bead-engaging flange, and having another bead-engaging portion, and having also a siphon-tube-receiving aperture; a siphon tube; and a container retaining means; said retaining means having a siphon tube receiving aperture; and assembling the sprayer by attaching the apron to the discharge head by snapping the resilient flange of the apron onto the bead and interlocking the bead with the other bead-engaging portion; inserting the siphon tube through the aperture in the apron into interlocking juxtaposition to the apron and discharge head, and positioning the siphon tube in operative juxtaposition to the discharge opening in said discharge head; inserting the free end of the siphon tube into said aperture therefor in the container-retaining means and positioning said retaining means in abutting relation to the pump wall; soldering the container retaining means to the pump wall, and soldering the siphon tube 50 to a portion of the assembled sprayer.

3. The method of constructing liquid sprayers which consists of providing a hand pump having a discharge head with a discharge opening therein, said discharge head attached to the hand pump by a bead; an apron having a resilient bead-engaging flange, and having a flangeless bead-engag-

ing portion, and having also a siphon-tube-receiving aperture; a siphon tube; and a container retaining means, said retaining means having a siphon-tube-receiving aperture; and assembling the sprayer by attaching the apron to the discharge head by snapping the resilient flange of the apron onto the bead and interlocking the bead with the flangeless bead-engaging portion; inserting the siphon tube through the aperture in the apron into interlocking juxtaposition to the apron and discharge head, and positioning the siphon tube in operative juxtaposition to the discharge opening in said discharge head; inserting the free end of the siphon tube into said aperture therefor in the container-retaining means, and positioning said retaining means in abutting relation to the pump wall; securing the container retaining means to the pump wall, and securing the siphon tube 80 against longitudinal movement thereof.

4. The method of constructing liquid sprayers which consists of providing a hand pump having a discharge head with a discharge opening therein, said discharge head attached to the hand pump by a bead; an apron having a resilient bead-engaging flange, and having a flangeless bead-engaging portion, and having also a siphon-tube-receiving aperture; a siphon tube; and a container retaining means, said retaining means having a siphon-tube-receiving aperture, and having also a solderable aperture; and assembling the sprayer by attaching the apron to the discharge head by snapping the resilient flange of the apron onto the bead and interlocking the bead with the flangeless bead-engaging portion; inserting the siphon tube through the aperture in the apron into interlocking juxtaposition to the apron and discharge head, and positioning the siphon tube in operative juxtaposition to the discharge opening in said discharge head; inserting the free end of the siphon tube into said aperture therefor in the container-retaining means, and positioning said retaining means in abutting relation to the pump wall; soldering the container retaining means through the solderable aperture therein to the pump wall, and soldering the siphon tube 100 to a portion of the assembled sprayer.

5. A sprayer including an air pump having a discharge head attached thereto by means of a bead, said discharge head having a discharge hole therein; an apron having siphon-tube-receiving-aperture and having also a resilient bead-engaging flange, and a flangeless bead-engaging portion, said resilient bead engaging flange and flangeless bead-engaging portion cooperating to engage the apron with the discharge head; a siphon tube extending through said siphon-tube-receiving aperture in the apron so as to lock the engagement of said apron with said discharge head, said siphon tube being in operative juxtaposition to the pump-discharge hole; container-re-

taining means having a siphon-tube-receiving aperture, the free end of the siphon tube extending into said aperture of the container-retaining means, and said container-retaining means being in abutting relation to the pump wall and soldered thereto.

6. A sprayer including an air pump having a discharge head attached thereto by means of a bead, said discharge head having a discharge hole therein; an apron having a siphon-tube-receiving aperture and having also a bead-engaging flange, said bead-engaging flange adapted to engage the apron with the discharge head; a siphon tube extending through said siphon-tube-receiving aperture in the apron so as to lock the engagement of said apron with said discharge head, said siphon tube being in operative juxtaposition with the pump-discharge hole; container-retaining means having a siphon-tube-receiving aperture, the free end of the siphon tube extending into said aperture of the container-retaining means, and said container-retaining means being in abutting relation to the pump wall and soldered thereto.

7. A sprayer including an air pump having a discharge head attached thereto by means of a bead, said discharge head having a discharge hole therein; an apron having a siphon-tube-receiving aperture and having also a resilient bead-engaging flange, and another bead-engaging portion, said resilient bead-engaging flange and other bead-engaging portion cooperating to engage the apron with the discharge head; a siphon tube extending through said siphon-tube-receiving aperture in the apron so as to lock the engagement of said apron with said discharge head, said siphon tube being in operative juxtaposition with the pump-discharge hole; container-retaining means having a siphon-tube-receiving aperture, the free end of the siphon tube extending into said aperture of the container-retaining means, and said container-retaining means being in abutting relation to the pump wall and soldered thereto.

8. A sprayer including an air pump having a discharge head attached thereto by means of a bead, said discharge head having a discharge hole therein; an apron having a siphon-tube receiving aperture and having also a resilient bead-engaging flange, and another bead-engaging portion, said resilient bead engaging flange and other bead-engaging portion cooperating to engage the apron with the discharge head; a siphon tube extending through said siphon-tube-receiving aperture in the apron so as to lock the engagement of said apron with said discharge head, said siphon tube being in operative juxtaposition with the pump-discharge hole; container-retaining means having a siphon-tube-receiving aperture and a solderable aperture, the free end of the siphon tube extending into said siphon-tube-receiving

aperture of the container-retaining means, and said container-retaining means being in abutting relation to the pump wall and soldered thereto through the solderable aperture.

9. A sprayer including an air pump having a discharge head attached thereto by means of a bead, said discharge head having a discharge hole therein; an apron having a siphon-tube-receiving aperture and having also a resilient bead-engaging flange, and another bead-engaging portion, said resilient bead-engaging flange and other bead-engaging portion cooperating to engage the apron with the discharge head; a siphon tube extending through said siphon-tube-receiving aperture in the apron so as to lock the engagement of said apron with said discharge head, said siphon tube being in operative juxtaposition with the pump-discharge hole; and said siphon tube being secured against longitudinal movement thereof; container-retaining means having a siphon-tube-receiving aperture and a solderable aperture, the free end of the siphon tube extending into said siphon-tube-receiving aperture of the container-retaining means, and said container-retaining means being in abutting relation to the pump wall and soldered thereto through the solderable aperture.

10. A sprayer including an air pump having a discharge head attached thereto by means of a bead, said discharge head having a discharge hole therein; an apron having a bead-engaging flange adapted to engage the apron with the discharge head; a siphon tube, the upper portion of said siphon tube being intermediate said apron and said discharge head so as to lock the engagement of the apron with the discharge head, said siphon tube being in operative juxtaposition to the pump discharge hole; container-retaining means having a siphon-tube-receiving aperture, the free end of the siphon tube extending into said aperture of the container-retaining means, and said container-retaining means being in abutting relation to the pump and secured thereto.

In testimony whereof, I have hereunto set my hand and seal this 24th day of January, 1931.

CARL F. ELLSWORTH.
